UNITED STATES PATENT OFFICE.

HUGO C. KRAUSE, OF CHICAGO, ILLINOIS, ASSIGNOR, BY MESNE ASSIGNMENTS, TO THE GORIN & COMPANY, INCORPORATED, OF ILLINOIS.

ATTACHMENT FOR TYPE-WRITERS.

SPECIFICATION forming part of Letters Patent No. 613,421, dated November 1, 1898.

Application filed March 26, 1896. Serial No. 584,983. (No model.)

To all whom it may concern:

Be it known that I, HUGO C. KRAUSE, a citizen of the United States, residing at Chicago, in the county of Cook and State of Illinois, 5 have invented a new and useful Improvement in Type-Writers, of which the following is a specification.

This invention relates to attachments for type-writers.

10 The object of the invention is to provide a spacing attachment for type-writers for use in tabulating or billing work which is of simple and improved construction, easily understood and operated, and efficient in operation.

15 The invention is designed as an improvement on the construction shown, described, and claimed in Patent No. 559,449, dated May 5, 1896, to Fred P. Gorin; and it consists, substantially, in the construction, combination, location, and relative arrangement of parts, all as will be more fully hereinafter set forth, as shown in the accompanying drawings, and finally pointed out in the appended claims.

25 Referring to the accompanying drawings and to the various views and reference signs appearing thereon, Figure 1 is a plan view of a construction embodying the invention detached from the machine. Fig. 2 is a trans-

30 verse sectional view of the same, taken on the line 2 2, Fig. 1. Fig. 3 is a detached broken detail view, in side elevation, illustrating a means through which the paper-carriage feed mechanism is released. Fig. 4 is a longitudi-

35 nal sectional view taken on the line 4 4, Fig. 1, the frame of the type-writing machine being indicated in cross-sectional outline, showing the connection of the attachment to the paper-carriage and to the carriage-feed release. Fig. 5 is a detached broken detail view, parts being in section, showing the manner of operating the carriage-feed release.

The same part is indicated by the same reference sign wherever it occurs throughout the 45 several views.

Reference sign A indicates the framework of a type-writing machine; B, the paper-carriage; C, the pivoted rack-bar carried by the paper-carriage and forming part of the usual 50 step-by-step feeding mechanism for the paper-carriage. These several parts may be

of the usual or any suitable, convenient, or well-known form of arrangement and of any type of machine, and as these parts form no part of the present invention detailed illustration and description thereof in the present instance are unnecessary.

Reference-letter D designates the frame upon which the operating parts of the spacing attachment are mounted. This frame 60 may be arranged in any suitable or convenient manner with reference to the particular type of machine to which the attachment is to be applied. I have shown the attachment as applied to a Remington machine, and 65 in the form shown, to which, however, I do not desire to be limited or restricted, the frame D forms a base upon which the machine rests, the front and rear cross-bars of frame D being provided with seats 6, adapted to receive 70 the side frames of the type-writer machine.

Mounted upon or carried by the frame D is a pivot stud or bolt 7, upon which is pivotally mounted to vibrate a bracket 8, upon which are mounted the various parts of the attachment hereinafter to be described and which has suitable connections with the paper-carriage and its feed-release bar. In the particular form shown, to which, however, I do not desire to be limited, the bracket is in the 75 form of a double segment, carrying on one side of its pivot the auxiliary keys and connected on the other side of its pivot to the paper-carriage and release-bar, as above mentioned.

The connection with the paper-carriage may be effected in any suitable manner whereby the bracket 8 is swung or vibrated upon its pivot coincidently with the movement of the paper-carriage and to a proportionate extent. 90 In the particular form shown, to which, however, I do not desire to be limited, I attach one end of a connection 9 to the rearwardly-extending segment of bracket 8, as at 10, and connect in any suitable manner the other end 95 of said connection to any convenient part of said paper-carriage, as at 11, Fig. 4. In order to secure the proper lead for connection 9, I may provide suitable guides 12 13 and mount the same adjustably, as by slot 14 and bolt 15, upon the frame of the type-writer, and, if desired, and in order to reduce fric-

tion, the guides 12 13 may comprise rollers. By the adjustment of the guides the proper tension may be maintained in connection 9 and slack therein may be readily taken up.

5 In a similar manner the end of a suitable connection 16 is attached at one end to the rear segment of bracket 8 and thence leads over adjustable guides similar in all respects to those above described for connection 9, and 10 the opposite end of said connection is so connected in any suitable manner to the rack-bar C of the paper-carriage feed mechanism as to be caused to move with the carriage and in addition to cause under suitable conditions the rack-bar to be rocked about its pivots and out of engagement with the ratchet-teeth, thereby disconnecting the paper-carriage from its usual or step-by-step feed mechanism. The special manner of effecting such 15 connection will of course vary with the different types of machines and with the exigencies of the particular machine. I have shown, therefore, a conventional method of such attachment, to which I do not desire to be limited, wherein the end of connection 16 is attached to a crank-arm 17, depending from a rock-shaft 18, said rock-shaft having an oppositely-extending arm 19, arranged to engage when said shaft is rocked with an arm 20, suitably connected to the pivoted rack-bar C of the paper-carriage feed mechanism. From this construction it will be seen that when a pull is exerted upon connection 16 the shaft 18 is rocked, the arm 20 is depressed by 25 the engagement therewith of crank-arm 19, and the rack-bar C is rocked out of engagement with the ratchet feed-dogs. It will be distinctly understood, however, that my invention is not limited to the specific form 30 and arrangement of parts, for many variations therefrom would readily suggest themselves to persons skilled in the art and still fall within the scope of my invention, the essential and generic idea of which is that 35 40 45 50 55 60 65 70 75 80 85 90 95 100 105 110 115 120 125 130 135

The particular form of connections 9 and 16 is unimportant. I have shown these connections as flexible bands, though it is evident that any other suitable or convenient form may be employed. It will be observed that the ends, respectively, of connections 9 and 16 are carried to that side of the segment of bracket 8 farthest from the side of the machine where said connections are attached to the carriage. From this construction it will be seen that the front segment of bracket 8—that is, the segment on the opposite side 60 of pivot-bolt 7—will be moved or swung in the same direction coincidently with and proportionately to the movement of the paper-carriage.

In order to release the paper-carriage from 65 its feed mechanism when the spacing attachment forming the subject of the present invention is brought into use, it is desirable to

provide means whereby the pull on connection 16 may be effected independently of the paper-carriage. Many different forms of mechanism for accomplishing this result may be devised, and therefore, while I have shown an operative embodiment of the idea, I do not desire to be limited thereto. In the particular form shown, instead of attaching the segment or bracket end of connection 16 directly to said segment or bracket, I attach said end to a link 21, carried by one arm of a bell-crank lever 22, pivotally mounted on the bracket 8. To the other arm of said bell-crank lever is 80 connected a pitman or link 23, which in turn is connected to a lever 24, pivoted upon the bracket and suitably and conveniently arranged to be engaged by the auxiliary keys, hereinafter to be described, when said keys 85 are actuated, as will presently be more fully explained. The extent to which connection 16 may be thus actuated may be varied by varying the extent to which bell-crank lever 22 is rocked. This variation may be conveniently secured by varying the point of connection of link 23 with one arm of said lever, as by providing said arm with a series of holes, in any one of which the end of pitman 23 may be secured. From this construction it will 95 be seen that when arm 24 is rocked a pull is exerted upon pitman or connecting-link 23, which in turn rocks bell-crank lever 22, and hence through link 21 effects a pull upon connection 16, thereby rocking rack-bar C out of engagement with the carriage-feed dogs.

I will now describe the construction and arrangement of parts whereby the arm 24 is rocked to effect a disengagement of the paper-carriage from its feed mechanism. In 105 suitable side flanges 25 26, formed upon a suitable forwardly-projecting part of frame D, is mounted a pin 27, upon which are independently pivoted a series of bars 28, having their forward or outer ends projecting 110 slightly beyond the casing formed by said flanges, and which projecting ends are preferably, though not necessarily, beveled upon the lower and outer edges thereof, as shown at 29. (See Fig. 2.) The bars 28 are mounted 115 independently of each other, except, for compactness and convenience of construction, they may be mounted upon the same pivot-pin 27. A spring 30 may be arranged to bear against each of said bars to normally elevate 120 the outer ends thereof. The inner ends of all of said bars are arranged underneath a cross and, preferably, a curved bar 31, carried by or forming part of the pivoted arms 24, said arms in the particular form shown being 125 pivoted upon the sleeve or hub by which bracket 8 is pivotally mounted upon pivot-stud 7. From this construction it will be seen that when the forward or outer end of any of the bars 28 is depressed the inner or 130 rearward end of said bar is raised, thereby effecting a raising of cross-bar 31, and hence a rocking of the arm 24, and consequently an actuation of connection 16, thereby releasing

the paper-carriage feed from its feed mechanism.

Any suitable or convenient construction and arrangement may be provided for manipulating the bars 28 at will. I have shown an operative embodiment of means for accomplishing the desired results, wherein I pivotally mount a series of key-bars 32 in any suitable or convenient manner—as, for instance, in a bracket formed upon or carried by frame D—and suitably connect the key-bars 32 with the rear ends of the bars 28, there being as many key-bars 32 as there are bars 28. Each key-bar carries a suitable key, as shown, and it will be understood that the keys are supplemental and additional to the type-keys of the machine, and from the foregoing description it will be seen that by employing the frame D as a supporting base for the type-writer machine the auxiliary keys are conveniently and handily arranged at the front of the machine and do not in any manner interfere with the operation of or space occupied by the usual keyboard of the machine. It will also be seen from the foregoing description that when any one of the auxiliary keys is depressed the rear end of its corresponding bar 28 is raised and the front end of said bar lowered, and resulting from this movement of bar 28 the paper-carriage is released from its feed mechanism. Carried by the forwardly-extending segment or portion of bracket 8 is a bar 33, upon which are mounted the adjustable stops or collars 34. The relative arrangement of stop-bar 33 with respect to the forwardly-projecting ends of bars 28 is such that when the front ends of said bars are depressed they will form a stop against which the collars 34 will impinge as the bar upon which said collars are mounted is swung or moved with bracket 8, thereby forming a stop for the paper-feed carriage at the required or desired point, since the operation of depressing the outer end of bar 28 also releases the carriage from its feed mechanism and the movement of the bracket 8 and the paper-carriage is synchronous.

By adjusting the collars 34 the point at which the carriage is stopped may be regulated and varied at will. As shown, the bars 28 are arranged in close proximity to each other, side by side, and each bar is of a thickness corresponding to a letter-space on the usual spacing-scale of the machine. Therefore from the foregoing description it will be seen that by adjusting the collars 34 upon stop-arm 33 to the required point and by suitably manipulating the auxiliary keys the paper-carriage is released from its feed mechanism and is moved under the influence of its controlling-spring, and coincidently with such movement rocking said bracket 8 until the stop-collar impinges upon the lowered projecting front end of the particular bar 28 which has been actuated, thereby arresting the carriage at the required point—say, for

instance and by way of illustration, at the point "40" of the ordinary spacing-scale. Now suppose it is desired to record a vertical column of figures of varying denominations with all the units falling directly under each other at a point on the page determined by the spacing-mark "40" of the spacing-scale, and the first number of the column to be recorded is of the "tens" denomination. Then the stop-collar 34 is adjusted to the required point on stop-bar to arrest the paper-carriage at the point "40," when the auxiliary key marked "Units" is manipulated. Then by pressing the auxiliary key marked "Tens" the paper-carriage is released from its feed and is arrested at a point one letter-space removed from the spacing-mark "40." The first figure of the number to be recorded is then written with ordinary type, and the ordinary step-by-step feed mechanism of the carriage effects a feed of said carriage into position to record the units figure of the number at the point "40," as previously determined upon. In like manner on the next line the carriage may be released and arrested at a point two letter-spaces removed from the point "40" to record the first figure of a number of the denomination of "hundreds" by manipulating the hundreds auxiliary key, and so on for each succeeding line. The provision of several stop-collars enables several columns to be recorded at different points on the same page. The shock and jar in the construction and operation above described is not communicated to the paper-carriage nor to any of the delicate parts of the type-writer mechanism, but is borne entirely by the attachment and is largely taken up in the connections, which, as explained, are preferably flexible between the attachment and the paper-carriage.

It may sometimes happen that the stop-bar 33 will occupy a position such that a collar 34 thereon offers an obstruction to the depression of a bar 28 just at the time when it is desired to depress said bar, thereby rendering it impossible to depress said bar 28. In order to avoid such a contingency, I so mount the entire bracket that said bracket is movable back and forth, and I bevel off the lower forward corner of the bars 28, as at 29, so that if a bar 28 is depressed and engages a collar 34 by exerting a little pressure the inclined surface 29 will cause the bracket 8 to be moved forwardly, thereby moving the stop-bar 33 and the collar 34 thereon out of the way of the bar 28, and hence permitting the actuation of the spacing attachment, as above explained. It will be observed, however, that the forward movement of the bracket 8 under the conditions referred to should be against the action of a spring which would normally tend to return it, to the end that the next stop-collar 34 would impinge upon the depressed end of the arm 28 and so effect an arrest of the movement of the paper-carriage. This idea may be embodied in many different specific forms of apparatus and still fall within

the scope of my invention. I have shown one form of apparatus for accomplishing the desired object, which is designed to be merely an operative embodiment of the idea, 5 wherein the frame D is suitably grooved to receive a movable slide 35, which is formed with or carries the pivot-pin 7, upon which the bracket 8 is pivoted. A suitable spring 37 is interposed between said slide 35 and a 10 stop, as 36, upon frame D. From this construction it will be seen that when bracket 8 is moved forwardly under the influence of the engagement of the inclined surface 29 of a bar 28 with a stop-collar 34 when such bar 15 is depressed the pivot-pin 7 and its slide 35 are also moved, and such movement is against the action of the spring 37. As soon as the bracket 8 has been moved forward a sufficient 20 distance for the obstructing stop-collar to be cleared by the end of bar 28, so that said arm may be fully depressed, the paper-carriage will have been released from its feed, and the movement thereof will cause a swinging motion to be imparted to bracket 8, which will 25 carry the obstructing stop-collar past the depressed end of bar 28, whereupon under the influence of springs 37 the bracket 8 will be moved rearwardly again and into position for the next stop-collar to impinge against the 30 depressed end of the bar 28. In order to permit of this endwise movement of bracket 8 and also to permit of the swinging movement of said bracket and still retain at all times such a rotation of the parts that a manipulation 35 of an auxiliary key will effect a release of the paper-carriage from its feed, I arrange the pivoted arm 31, as shown, so that as said arm partakes of the movements of bracket 8 it will still and at all times overhang the rear 40 end of the bars 28.

The operation will be readily seen and understood from the foregoing description.

While I have shown one operative embodiment of the broad principles of my invention, 45 it will be understood, of course, that the same principles may be embodied in widely-differing specific forms of mechanism. I do not desire, therefore, to be limited or restricted to the exact form, construction, and arrangement 50 of parts shown and described; but

What I claim as new and useful and of my own invention, and desire to secure by Letters Patent of the United States, is—

1. In a type-writer, a spacing attachment, 55 comprising a movable bracket, connections from said bracket to the paper-carriage, whereby said carriage and bracket move coincidently, a stop carried by said bracket, and means arranged to release said carriage from its feed mechanism and to engage said stop, whereby said carriage is arrested; as and for the purpose set forth.

2. In a type-writer, a spacing attachment, 60 comprising a pivoted bracket, connections between said bracket and the paper-carriage, whereby said bracket is swung about its pivot 65 coincidently with the movement of said car-

riage, stops carried by said bracket, and means arranged to release said carriage from its feed mechanism and to arrest the same at 70 a predetermined point; as and for the purpose set forth.

3. In a type-writer, a spacing attachment, 75 comprising a movable bracket, connections from said bracket to the paper-carriage, whereby said carriage and bracket move coincidently, a stop carried by said bracket, a series of bars arranged a letter-space distance apart, each of said bars arranged to release said carriage from its feed mechanism and to 80 engage said stop, whereby said carriage is arrested at predetermined distances from a given point; as and for the purpose set forth.

4. In a type-writer, a spacing attachment, 85 comprising a movable bracket, connections between said bracket and the paper-carriage, whereby said bracket and carriage move coincidently, a series of adjustable stops carried by said bracket, means arranged to disengage said carriage from its feed and to be engaged 90 by one of said stops, whereby the movement of the carriage when released from its feed is arrested at a predetermined point; as and for the purpose set forth.

5. In a type-writer, a spacing attachment, 95 comprising a bracket, connected to and moving coincidently with the paper-carriage, stops carried by said bracket, a series of auxiliary bars arranged, when actuated, to be projected into position to be engaged by said stops, and 100 means operated by the actuation of said bars for releasing the paper-carriage from its feed mechanism; as and for the purpose set forth.

6. In a type-writer, a spacing attachment, 105 comprising a frame, a bracket mounted thereon for lateral and longitudinal movement, connections between said bracket and the paper-carriage, whereby lateral movement is imparted to said bracket coincidently with the movement of the carriage, stops carried 110 by said bracket, and means, arranged to disengage said carriage and to be engaged by said stops, whereby said carriage is arrested; as and for the purpose set forth.

7. In a type-writer, a spacing attachment, 115 comprising a frame, a bracket mounted thereon for lateral and longitudinal movement, a spring arranged to oppose the longitudinal movement of said bracket, connections between said bracket and the paper-carriage, 120 whereby lateral movement is imparted to said bracket coincidently with the movement of the carriage, bars arranged to disengage said carriage from its feed, said bars adapted to move said bracket longitudinally, and stops 125 carried by said bracket, adapted to engage said bars, whereby the movement of the paper-carriage is arrested; as and for the purpose set forth.

8. In a type-writer, a spacing attachment 130 comprising a movable bracket, flexible connections between said bracket and the paper-carriage, stops carried by said bracket, and bars arranged to disengage the paper-carriage

from its feed mechanism and to be engaged by said stops, whereby the movement of the carriage is arrested; as set forth.

9. In a type-writer, a spacing attachment, comprising a swinging bracket, means connected at one end to said bracket and connected at the opposite end to the paper-carriage, a pivoted lever carried by said bracket, and means connected at one end to said lever and at the opposite end to means for releasing the paper-carriage from its feed, and means for actuating said lever, whereby the carriage-feed is disengaged and means for arresting the carriage at a predetermined point; 15 as and for the purpose set forth.

10. In a type-writer, a spacing attachment, comprising a series of auxiliary keys, pivoted bars actuated thereby, a swinging bracket, connections between said bracket and the paper-carriage, whereby the two move coincidently, stops carried by said bracket, arranged to engage said bars, and means actuated by the rocking of said bars, for disengaging the carriage from its feed; as and for 25 the purpose set forth.

11. In a type-writer, a spacing attachment, comprising a series of auxiliary keys, a corresponding series of pivoted bars actuated thereby, a swinging bracket connected to move with the paper-carriage and carrying stops, said stops adapted to engage said bars when rocked by said keys to arrest the movement of said carriage, and means actuated by said bars for releasing the carriage from its feed mechanism; as and for the purpose set forth.

12. In a type-writer, a spacing attachment, comprising a series of auxiliary keys, a corresponding series of pivoted bars actuated thereby, a swinging bracket connected to move with the paper-carriage and carrying stops adapted to engage said bars to arrest the movement of the carriage, a pivoted lever carried by said bracket, and arranged to be rocked by the actuation of said bars, and means actuated by the rocking of said lever for disengaging the carriage from its feed; as and for the purpose set forth.

13. In a type-writer, a spacing attachment, comprising a series of auxiliary keys, a corresponding series of pivoted bars actuated thereby, a swinging bracket, a lever pivotally mounted on said bracket and adapted to be engaged and rocked by said bars, a cord connected at one end to said bracket and at the opposite end to the paper-carriage, a second cord connected at one end to said pivoted lever and at the other end to the feed-rack bar at the opposite side of the carriage, and stops 60 carried by said bracket; as and for the purpose set forth.

14. In a type-writer, a paper-carriage, a rock-shaft mounted thereon, an arm carried by said shaft, arranged to engage the feed-

rack of said carriage, a swinging bracket, a connection between said bracket and another arm on said shaft, a second connection between said bracket and the opposite side of said carriage, stops carried by said bracket, bars arranged to be projected into the path of movement of said stops, and means actuated by the movement of said bars for rocking said shaft upon the carriage, thereby releasing the carriage from its feed; as and for the purpose set forth.

15. In a type-writer, a spacing attachment, comprising a bracket mounted on a movable pivot, connections between the carriage and said movable bracket, whereby the movement of said bracket about its pivot is coincident with the movement of said carriage, stops carried by said bracket, keys, means actuated thereby for engaging said stops, said means adapted to move said pivot, and means also actuated by said keys for releasing the carriage from its feed; as and for the purpose set forth.

16. In a type-writer, a frame, adapted to form a base to receive the machine, a swinging bracket mounted thereon and connected to move with the paper-carriage, auxiliary keys mounted on said frame, stops carried by said bracket, and means actuated by said keys for releasing the carriage and for engaging said stops; as and for the purpose set forth.

17. In a type-writer, a swinging bracket, a flexible connection connected at one end to the side of the paper-carriage and at the other end to the opposite side of the bracket, and a second flexible connection connected at one end to the opposite side of the carriage and at its other end to the corresponding opposite side of the bracket, stops carried by the bracket, a series of keys, means actuated thereby for engaging said stops, and means also actuated thereby for disengaging the carriage from its feed; as and for the purpose set forth.

18. In a type-writer, a swinging bracket, connected to move with the paper-carriage and carrying stops, a series of auxiliary keys, a corresponding series of pivoted bars, adapted to be rocked by said keys into position to be engaged by said stops, a lever pivotally mounted on said bracket and arranged to be engaged and rocked by said bars in whatever position said bracket may be swung, and means actuated by said lever for disengaging the carriage from its feed; as and for the purpose set forth.

In witness whereof I have hereunto set my hand, this 11th day of March, 1896, in the presence of the subscribing witnesses.

HUGO C. KRAUSE.
